UNITED STATES PATENT OFFICE.

GEORGE W. KUENNETH, OF PATERSON, NEW JERSEY.

BEAMING MECHANISM FOR WARPING AND BEAMING MACHINES.

1,099,653.

Specification of Letters Patent.

Patented June 9, 1914.

Application filed July 22, 1909. Serial No. 508,948.

To all whom it may concern:

Be it known that I, GEORGE W. KUENNETH, a citizen of the United States, residing in Paterson, Passaic county, New Jersey, have invented a certain new and useful Improvement in Beaming Mechanisms for Warping and Beaming Machines; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

This invention relates to warping and beaming machines and particularly to the beaming mechanism thereof.

The type of beaming mechanism to which my invention is applied is that employed in the beaming of warps for ribbons, or in other instances where narrow warps are beamed, in which two or more beams or spools are rotated at once. In a beaming mechanism of this nature it is desirable that each spool or beam be capable of being independently removed, so that a fresh warp may be started thereon when the winding of one has been completed. It is also important that the mechanism be so constructed as to allow for setting each beam in operative position with positive accuracy with respect to the reel of the warping machine each time a removal of a beam and the re-establishment thereof, or of its counterpart, is effected; and that each beam, when in operative position, shall run true in its bearings and be as free as possible from undue vibration, as otherwise the necessary uniform disposition of the threads of the warp will be prevented. It is important, further, that the beams be so arranged as to economize space laterally of the machine, whereby to increase as much as possible the number of warps which can be run through the machine at a time.

My object, among others, is therefore to provide a beaming mechanism by which these results may be accomplished in a more perfect manner than heretofore, and in the use of which various other advantages, involving a saving of space, time and skill, may follow.

According to my invention, a plurality of beams are arranged with their axes substantially parallel and each beam offset with

relation to the adjoining beam in the direction of the length of their axes, and a common driving and supporting means receives the adjoining ends of said beams; having, therefore, only one driving and supporting means for two beams, instead of two, one for each beam, I am enabled to save space which may be utilized to accommodate more warps than would otherwise be possible, the saving of space thus effected being obviously considerable in a warping machine having the usual transverse dimension. Further the rotary part which directly carries the beam at one end of the latter is arranged in another rotary part so as to be adjustable axially of the beam in the latter, whereby such beam may be set at various positions laterally of the machine or removed for the purpose of substituting another beam of different width.

In the accompanying drawings, Figure 1 is a view in side elevation of the beaming end of a warping and beaming machine constructed in accordance with my improvement; Fig. 2 is a plan view of the beaming mechanism; Fig. 3 is a view on a larger scale of one of the driving heads for the beams, showing the same partly in plan but mainly in horizontal section on the line $x-x$ in Fig. 4; Fig. 4 is a vertical sectional view of what is shown in Fig. 3 approximately on the line $y-y$ in said figure. Fig. 5 shows in rear elevation the lower portion of what is shown in Figs. 3 and 4, that is, the driving shaft, the pinion splined thereon and the lower rear portion of the gear casting; Fig. 6 is a vertical sectional view on the same scale as Figs. 3, 4 and 5, showing the means for supporting the driving heads and dead heads, and showing one of said dead heads thereon in side elevation; Fig. 7 is a view partly in front elevation, and partly in vertical section, of what is shown in Fig. 6; Fig. 8 illustrates a modification of what is shown in Figs. 6 and 7, Fig. 8 being a side elevation; and Fig. 9 is a fragmentary view in front elevation of what is shown in Fig. 8.

In the drawings, a designates the frame of a warping and beaming machine and b its reel. In the brackets c and d is journaled the driving shaft e , carrying the fast and loose pulleys f, f' and a pinion g , which meshes with the gear h (journaled in bracket c) for rotating the chain clutch i whereby power is transmitted to a beam

supported in said clutch and in another bracket (not shown) at the opposite side of the machine, when the beaming of a warp for broad goods is to be effected. On the 5 shaft *e* is arranged a series of pinions *j* which are splined thereto.

h designates two parallel channel irons connecting and bolted to the sides of the frame *a*. These channel irons support the 10 driving heads and the dead heads for the beams; the beams are arranged in pairs, the beams of each pair being laterally offset from each other and having a common driving head supporting their adjoining ends 15 and separate dead heads supporting their outer ends.

Referring, first, to the driving heads, *l* 20 designates a gear casing divided vertically into two parts which are counterparts of each other and which are clamped together by means of screws or the like *m*, two or more of which may penetrate their contacting bosses *n*. In bearings *o*, disposed preferably in the same horizontal plane, are 25 journaled the sleeve portions *p* of sprockets *q*, the rear one of said sleeve portions having formed integrally therewith the gear *r*.

s is an endless sprocket chain extending around the sprockets *q*. Each sleeve *p* is 30 formed with an internal spline *t*. In each sleeve is introduced the shank *u* of a face-plate *v*, said shanks being introduced from the opposite ends of the two sleeves, so that one face plate stands at one side, and the 35 other at the other side, of the bracket *l*. The face plate has the usual central hole *w* to receive the trunnion and beam and the usual stud *x* interlocking the beam with the face-plate.

40 Into the free end of the shank *u* is tapped the threaded portion *y* of a hand-screw *z* having a smooth tapered free end *l*, adapted to impinge against a key *2* movable radially in the shank and having a flattened portion *3* received by the spline *t*. This arrangement makes it possible, by first loosening the hand nut, then shifting the face-plate axially, and then tightening the hand nut so that the key is bound between the 45 sleeve *p* and the tapered end of the hand nut, to adjust the face-plate in the sleeve longitudinally of its axis.

The two halves of the bracket or gear casing *l* are formed with mating inwardly 50 projecting flanges *4* which are continuous except at the back of the bracket, where a downwardly opening recess *5* is formed for the reception of one of the pinions *j*, which may be slid along the shaft *e* so as to be 55 received by the bracket *l*, which, being then dropped over it, limits it against lateral movement therein (see Fig. 5); any subsequent lateral movement of the bracket will cause the pinion to move with the bracket. 60 The pinion meshes with gear *r*. The bracket

is detachably held in place, so as to be capable of being raised and then dropped over a pinion *j*, as will hereinafter appear.

Referring now to the dead-heads, *6* (Fig. 6) designates a two-armed bracket having 70 cylindrical openings *7* in its upwardly extending arms adapted to receive the dead-spindles *8* held for adjustment axially in said openings by the screws *9*, said dead-spindles being bored at *10* to receive the 75 trunnions of the beams. It will be understood that in the assembled arrangement of the parts, the dead-spindles *8* are axially alined with the corresponding face plates of the driving-heads.

The driving-heads and dead-heads are 80 designed to be adjustable laterally of the machine, and for this purpose each is received by the groove *11* in the upper part of a saddle *12* which has a squared projection 85 *13* projecting downwardly and fitting between the channel irons *h*. Each driving-head (and each dead-head), its saddle *12*, and the guideway formed by the two channel irons are penetrated by a bolt *14* carrying 90 a nut *15* which may be screwed up against a washer *16* engaging the under side of the guideway.

17 designates the beams, each having one trunnion set in a face plate *v* and the other in a dead-spindle *8*; it will be understood 95 that each beam has a notch to receive the stud *x* on the face plate.

In Figs. 8 and 9, the guideway is formed by two parallel bars *18*. The saddle *19* to 100 support the driving-head (or dead-head) has the forked portions *20* each adapted to receive a bar *18*. *21* is a plate which may be clamped against the under side of the bars *18* by means of the bolt *22* and nut *23*. The saddle *19* for each driving-head is preferably bifurcated, as shown in Fig. 9, so as to straddle the pinion *j* and cause it to partake of the lateral movement of the driving-head.

110 In view of the foregoing it will be seen that, since a single driving-head is employed in each instance for two beams, space is saved for the accommodation of beams which would otherwise not be utilized. Further that, since it only requires the manipulation of nuts *15* to make it possible to shift the driving heads and dead-heads laterally, the mechanism may be quickly altered to receive beams having lengths different from those previously used or to change the positions of the beams relatively to the reel. Again, that adjustment of each beam relatively to the reel may be accomplished to a nicety by manipulating the hand screw *z*, 115 and when such adjustment has once been effected, the face-plates maintain a definite relation to the reel and serve as gages with reference to which each beam and its dead-head are set when a filled beam is to be 120 125 130

taken out and a fresh one introduced; this last feature is of considerable value in that, once the face-plates have been adjusted in proper relation to the reel, the attention of 5 a person more skilled in the operation of beaming than the attendant directly assigned to the machine, is not required in order to insure the proper disposition of the beams each time they are changed.

10 Having thus fully described my invention, what I claim as new and desire to secure by Letters Patent is:

1. The combination of a support, two beams arranged in offset relation to each 15 other and with their axes substantially parallel, a unitary driving and supporting means for said beams movable on said support in the direction of the length of the axes of said beams and receiving the adjoining 20 ends of the latter, and means affording support for the other ends of the beams, substantially as described.

2. The combination of a support, a rotary shaft, two beams arranged in offset 25 relation to each other and with their axes substantially parallel with the shaft, means for supporting the adjoining and relatively outer ends of the beams comprising a bracket receiving the adjoining ends of both beams 30 and movable on said support substantially parallel with said shaft, and power transmitting mechanism movable with said bracket and operatively connecting the shaft with both beams, substantially as described.

35 3. The combination of a support, a rotary shaft, two beams arranged in offset relation to each other and with their axes substantially parallel with the shaft, means for supporting the adjoining and relatively outer ends of the beams comprising a casing 40 receiving the adjoining ends of both beams and movable on said support substantially parallel with said shaft, and power-transmitting mechanism inclosed in and movable with said casing and operatively connecting the shaft with both beams, substantially as described.

4. A beaming mechanism for a beaming machine consisting, in combination, of the 50 beam and means for supporting and effecting rotation of said beam including a bracket, a rotary structure journaled in said bracket and comprising a rotary supporting part alined with the beam and a rotary 55 supported part carried by the supporting part and also alined with and engaging the beam and adjustable axially thereof, and means, contained in said structure and protruding therefrom axially thereof, for securing the supported part to the supporting part in any position to which said supported part is axially adjustable.

5. A beaming mechanism for a beaming machine consisting, in combination, of the beam and means for supporting and effecting 65 rotation of said beam including an inclosing casing having opposed walls, a rotary structure comprising a supporting part journaled in said walls and held thereby against axial movement and a supported 70 part carried by the supporting part and adjustable therein axially thereof and engaging the beam, and means, contained in said structure and protruding therefrom axially thereof, for securing the supported 75 part to the supporting part in any position to which said supported part is axially adjustable.

6. In a beaming mechanism, the combination of a beam, and means for supporting and effecting the rotation of said beam comprising 80 a bracket, a rotary part journaled in said bracket in axial alinement with the beam and having an internal longitudinal spline, another part disposed and movable 85 axially in said rotary part, a key radially movable in the axially movable part and engaging in the spline of said rotary part, and a screw tapped in the axially movable part and adapted to impinge against said 90 key, substantially as described.

7. In a beaming mechanism, the combination of a beam, and means for supporting and effecting rotation of said beam comprising 95 a bracket, a rotary part journaled in said bracket in axial alinement with the beam, another part disposed and movable axially in said rotary part, a key radially movable in the axially movable part into engagement with said rotary part, and a 100 key-operating device axially movable in said axially movable part.

8. In a beaming mechanism, the combination of a support, a bracket movable on the support, a shaft journaled in the support 105 parallel with the path of movement of the bracket on the support, said bracket having an opening opposite to the shaft and being movable toward and from the shaft, a pinion splined on the shaft and received by the 110 opening in the bracket, a beam, and means for supporting one end of the beam and transmitting rotary motion to the beam comprising a gear revolvably arranged in said bracket and meshing with the pinion, substantially as described.

In testimony that I claim the foregoing, I have hereunto set my hand this 20th day of July, 1909.

GEO. W. KUENNETH.
